ELECTRIC RAILWAY.

1,064,481.

Specification of Letters Patent. Patented Apr. 26, 1913.

Application filed May 20, 1905. Serial No. 261,369.

To all whom it may concern:

Be it known that J. Louis H. THULLEN, a citizen of the United States, residing at Edgewood Park, in the county of Allegheny and State of Pennsylvania, have invented certain new and useful Improvements in Electric Railways, of which the following is a specification.

My invention relates to electric railways where the track rails are used as part of the return for the propulsion current.

My invention has particular reference to the bonding of the track rails.

I will describe an electric railway embodying my invention and then point out the novel features thereof in claims.

In the accompanying drawing, Figures 1 and 2 are diagrammatic views of portions of two electric railways, each embodying my invention.

Similar letters of reference designate corresponding parts in both of the figures.

Referring to Fig. 1, I have shown two tracks T and T', and in Fig. 2, one track T. The tracks may be divided into sections S, S¹, S² and S³ etc., each section being separated from its adjacent sections by insulation n. G designates a source of current supply for the propulsion of cars upon the railway, having one pole connected to the trolley wire or third rail H, and the other pole connected to the track rails, and in the present case we will assume it to be supplying direct current. F designates a supplementary return conductor for the propulsion current which is connected in parallel to the track rails in the manner hereinafter described.

I will assume an alternating signaling current to be circulating in the track sections and this alternating current may be used for the control of signals. The cross bonds embodied in my invention are diagrammatically illustrated and are designated by the characters c, c¹, c², etc. They are made in the form of inductive bonds. Each of said inductive bonds comprises a core of iron or other magnetizable material having wound upon it a coil or coils of wire or other suitable conductor and one end of each of said coils is connected to one rail of a track, while the other end of the coil is connected to the opposite rail of the same

track. The cross bonds, c, etc. are so designed as to have very low ohmic resistance so as to allow a free passage of the propulsion current from rail to rail, but the self induction of the said coils is so high that they offer sufficient impedance to the alternating signaling current of the track circuit to choke the said alternating current down to an imperceptible amount, thereby effectually preventing any derangement of the signal system through a short-circuiting of the said alternating current in the track circuit. At d, d¹, etc. I provide an electrical connection from a point of or near the center of one cross bond to a point at or near the center of an adjacent cross bond in such a manner that the said electrical connection in conjunction with the cross bonds to which it is connected forms a bridge or bond across two rail insulations, as shown in Figs. 1 and 2. The bridge or bond so formed has a low ohmic resistance and will, therefore, not appreciably impair the conductivity of the return propulsion current through the track rails. The coil or coils on each bond and their connection with adjacent bonds or return conductors are so arranged that current from the rails will traverse the coil or coils in opposite directions, thereby preventing saturation of the iron core in the bond. If desired, cross bonds may be used between the rails to equalize any difference of potential between the rails.

In Fig. 1 I have shown two adjacent tracks forming part of the same railway system and when this condition obtains I employ a connection between each pair of cross bonds on one track T, as c¹, c², for example, and a corresponding adjacent pair of cross bonds c¹, c², on another track T', thus equalizing or dividing the return current load between the two tracks. At f, Fig. 1, I show an electrical connection between two single inductive cross bonds on adjacent tracks, and this is the mode of connection I employ between tracks at locations remote from track insulations or where no track insulations are used. At c¹ and c², Fig. 1, I show the method I employ of connecting one pole of the source G to the track rails and here I likewise use inductive cross bond between rails in order to choke down the alternating signaling cur-

rent of the track circuit and I connect the pole of the source G to points at or near the centers of the said cross bonds.

In Fig. 2 a supplementary return conductor F is shown such as is frequently employed to carry part of the return propulsion current load which would otherwise be carried entirely by the track rails. This supplementary return conductor may be in the form of a copper wire or cable laid or strung along the track or it may be an iron or steel structure upon which the track is laid or any other suitable conductor. At h, h^1 , h^2 , etc. I have shown my method of connecting this supplementary return to the track rails so as to form a common conductor with the said rails for the return current, and it will be seen that, as in the case of cross connections between tracks in Fig. 1, I here make my connections to points at or near the centers of the inductive cross bonds c , c^1 , c^2 , etc. thereby avoiding the danger of short circuiting the track rails as regards the alternating current flowing therein, but at the same time allowing a free path of low ohmic resistance for the propulsion current.

As here shown, the alternating signaling current for the track sections is supplied by an alternating current generator 6 which is connected with signaling mains 5 extending along the trackway. At each junction of adjacent sections I provide a transformer 7 the primary of which is connected with the signaling mains and the secondary with the rails of a track section. As shown in Fig. 1, each of these transformers comprises two secondaries one of which is connected with the rails of a section of track T and the other of which is connected with the rails of a section of track T^1 . In Fig. 2 each transformer comprises only one secondary for the reason that only one track is here shown. Each track section is also provided with a suitable relay 8 which is responsive to the alternating signaling current. Each relay controls a railway signal 9 for the corresponding track section by means of a local circuit in the usual and well known manner.

Claims—

1. An electric railway having two or more tracks and in which both rails of each track are used as a return for the propulsion current, in combination with cross bonds having a high impedance to a signaling current and a low ohmic resistance to a propulsion current, and means for electrically connecting the cross bonds of one track to the cross bonds of one or more adjacent tracks.

2. An electric railway having two or more tracks and in which one or both rails of each track are used as a return for the propulsion current, in combination with rail bonds having high impedance to a signaling current

and low ohmic resistance to a propulsion current, and means for electrically connecting the rail bonds of one track to the rail bonds of one or more adjacent tracks.

3. In combination, an electric railway having two or more tracks, a plurality of block sections for each track, track circuits for the block sections, a source of propulsion current and a source of signaling current, inductive bonds connected across the rails of each block adjacent the ends thereof and having high impedance for signaling current and low impedance for propulsion current, an electric connection from one bond to the adjacent bond, and an electric connection from a pair of bonds on one track to a pair of bonds on an adjacent track.

4. In an electric railway two or more tracks, a plurality of inductive cross bonds for each track, each cross bond connecting one rail of its track to the opposite rail, and a plurality of electric bonds connecting one or more cross bonds of one track to one or more cross bonds on each of the other tracks of the railway.

5. In an electric railway, a source of propulsion current, an inductive cross bond having high impedance to a signaling current and low ohmic resistance to a propulsion current connecting the rails on one side of the track to the rails on the other side of the track, and means for electrically connecting the said cross bond at a point at or near its center to one pole of the source of current supply, the other pole of said source being connected in the usual manner to a trolley wire or third rail or other equivalent conductor of the propulsion current.

6. In a signaling system of the type described, a plurality of pairs of parallel lines of rails included in the circuit of the propulsion current, means for cross-connecting said parallel lines of rails, said means comprising a conductor connected to one rail of each pair of rails and a conductor connected to one rail of each pair of rails through resistance bonds.

7. In a signaling system of the type described, a plurality of pairs of parallel lines of rails included in the circuit of the propulsion current, means for cross-connecting said parallel lines of rails, said means comprising a conductor connected to one rail of each pair of rails and a conductor connected to one rail of each pair of rails through devices which will obstruct the flow of an alternating current.

8. In combination, an electric railway having two or more tracks the rails of which are included in the circuit for the propulsion current, an inductive bond for each track connected across the rails of the track, and a conductor connecting substantially the middle point of the winding of the bond for one track with substantially the middle

point of the winding of the bond for another track.

9. In combination, an electric railway having a plurality of parallel tracks, block sections for each track formed by insulations in both lines of rails, inductive bonds connected across the rails of each block adjacent the ends of the block, a conductor connecting substantially the middle point of each bond with substantially the middle point of the adjacent bond for the adjacent block section,

and an electrical connection between a conductor for one track and a similar conductor for another track.

In testimony whereof I have signed my ¹⁵ name to this specification in the presence of two subscribed witnesses.
